UNITED STATES PATENT OFFICE.

FREDERICK D. SWEET, OF CLEVELAND, OHIO, ASSIGNOR TO THE SWEET-WEBSTER MANUFACTURING COMPANY, OF CLEVELAND, OHIO.

SEWING-MACHINE ATTACHMENT.

1,240,384.

Specification of Letters Patent. Patented Sept. 18, 1917.

Application filed August 9, 1916. Serial No. 113,847.

To all whom it may concern:

Be it known that I, FREDERICK D. SWEET, a citizen of the United States, residing at Cleveland, in the county of Cuyahoga and 5 State of Ohio, have invented a certain new and useful Improvement in Sewing-Machine Attachments, of which the following is a full, clear, and exact description.

The object of this invention is to provide 10 an inexpensive, easily operated, and highly efficient device adapted to be readily attached to a sewing machine, and capable of so automatically moving a piece of cloth beneath the reciprocating needle of the sewing machine that there will be formed along 15 each side of the line at which the button-hole is to be formed by subsequently slitting the cloth, a row of laterally extended stitches; and with which also the ends of the 20 buttonhole may be finished by stitches which extend laterally from the outer edge of one row of stitches to the outer edge of the other row of stitches.

The invention consists in the construction 25 and combination of parts shown in the drawings, hereinafter described and definitely pointed out in the appended claims.

In the drawings Figure 1 is a side view 30 of the invention applied to a sewing machine. Fig. 2 is a plan view thereof. Fig. 3 is a plan view when the cloth clamping lever has been removed. Fig. 4 is a sectional side elevation. Fig. 5 is a sectional end view when the vibrating workholder is in one of 35 its extremes of movement. Fig. 6 is a similar view when the vibrating workholder is in the other extreme of movement. Fig. 7 is a sectional plan view of certain parts of the device. Fig. 8 is a plan view partly 40 broken away of the rear end of the workholder. Fig. 9 is a plan view of the workholding foot. Fig. 10 is a side view of the workholding foot. Fig. 11 is a rear view of the rear end of the workholder. Fig. 12 45 is a sectional plan view of the feed screw and associated mechanism. Fig. 13 is a sectional side elevation of certain parts of the mechanism. Fig. 14 is a front elevation of the mechanism when applied to a sewing 50 machine.

The attachment includes a subbase plate 10 which is preferably constructed to take the place in the sewing machine of the ordinary needle plate, whereby the attachment will be secured to the sewing machine 55

in proper working relation thereto. A base plate 12 is secured on the subbase by means which permit a slight lateral movement of the base plate. The means for so securing the base plate to the subbase and the purpose 60 to be served by the lateral movement of the base plate will be presently explained.

On the base plate is a slide 15 movable between guides 13 forward and backward. Fixed to the slide and extending upward 65 therefrom is the forked standard 20 in which a rock shaft 21 is mounted. There is secured to this shaft and extended rearward therefrom a substantially horizontal lever 22 in which is a slot 22^a. The purpose of 70 this slot is to embrace a laterally projecting stud on the vertically reciprocating needle bar B of the sewing machine whereby this lever will be rocked up and down in synchronism with the corresponding movements of 75 the needle bar. Another arm 23 extends downward from this rock shaft and carries a spring pawl 24 which will engage a ratchet 25. This ratchet is a disk which is pivoted on a vertical stud 26 to the base 80 12, and has a plurality of upwardly projecting pins 25^a for the spring pawl to engage with. This ratchet is a part of a rotating member which also includes the gear disk 28 and the cam 29. It is obvious that 85 as the lever is rocked up and down by the needle bar, the rotating member, of which the ratchet is a part, will be turned step by step, or more specifically, it will be turned 90 through the arcual distance which corresponds with the distance between two adjacent pins 25^a on the ratchet every time the needle bar goes up, which it will be understood is at a time when the needle is clear 95 of the work.

A vibrating workholder 40 is pivoted to the slide by means of a vertical stud 50 located near the front end of each. Along the side of the work holder are the down-turned flanges 42, which extend close to 100 105 the edges of the cam 29. This cam has an unequal number of equally spaced projections 29^a, in the present case five. When a projection 29^a engages one of the downturned flanges 42 of the vibrating workholder it will rock the same on its pivot to the right or left, as the case may be; and it may so rock because when a cam projection is engaging one flange 42 there is no cam project- 110

tion in such proximity to the other flange on the vibrating workholder as will prevent such movement.

During each upward movement of the 5 needle the cam will be turned so as to withdraw the projection on the cam from engagement with the downturned flange on the workholder and so as to cause another projection on said cam to engage the opposite flange of the workholder and thereby 10 vibrate it in the opposite direction. The path traveled by the rear end of the workholder in these vibratory movements thereof will be about $\frac{1}{16}$ inch, and this movement of course determines the length of the stitch 15 made by the needle.

This workholder carries a work clamping lever 43 by which the work may be clamped down upon the upper surface of the rear end or jaw 41 of the workholder. 20 This lever 43 is pivoted near its middle, and it is actuated in the clamping direction by a spring 45 which is compressed between the front ends of the workholder and lever. In 25 the rear end or jaw 41 of the workholder 40 is a rearwardly extended slot 41^a, and in the jaw 44 of the lever 43 is a corresponding slot; said slots being longer than the buttonhole to be worked, and of a width sufficient to permit the lateral vibration of the 30 workholder while still keeping the slots 41^a and 44^a beneath the needle. To insure that the work shall be firmly held down on the jaw 41 of the workholder a slotted clamping plate 46 is placed beneath the jaw 44, which is the rear end of the lever 43 and the 35 plate 46 is pivoted to the jaw 44 on a lateral axis so that it will have a slight rocking movement that enables it to firmly grasp the work between it and the jaw of the lower workholder. The upwardly turned flanges 41^b are formed on the sides of the jaw 41,— and the cloth goes over them and is therefore so held up that it is not likely to get 45 under said work holder.

To facilitate the insertion of the work into the embrace of the workholder jaws, a bail 71 is pivoted to the front end of the workholder;—and it is so shaped that when 50 the jaw 44 is lifted by pressing down the front end of lever 43, the bail may be swung over said lever end, and thereby the jaw will be held up.

When the device is in operation and the 55 rear end of the workholder is vibrated back and forth so that the needle will go through the cloth at a point in close proximity to the subsequently to be cut slit or buttonhole, or through the cloth at a slight distance 60 back therefrom, it is necessary that the work be fed lengthwise of the buttonhole. To produce this result a feed screw 51 is used. This lies below the base plate 12 and is rotatably mounted at its front end in a bearing bracket 12^a fixed to and projecting from 65

said base. This feed screw carries a pinion 52 whose teeth engage the holes 28^a in gear disk 28 which is a part of the same rotating member of which the cam and ratchet are parts. Every time the ratchet is turned 70 through one of its arcual steps, the feed screw is correspondingly turned. The base plate 12 has its front edge 12^b downturned and the feed screw passes loosely through this flange. On the downturned front end 75 15^a of the slide 15 two levers 55 are pivoted on vertical axes, and each of these levers carries at its front end a half nut 56 which is intended to engage the feed screw, and will be automatically caused to engage it by 80 a spring 57 which is compressed between the rear ends of said levers. When this nut is so engaging the feed screw intermittent turning of the feed screw will advance the slide the short distance required between 85 two successive buttonhole making stitches. This screw induced feed movement of the slide is rearward. When it has progressed far enough, that is to say, when it has progressed a distance slightly greater than the 90 buttonhole, the slide may move forward to enable it to begin a new cycle of operation. In order that this may be done quickly and easily, the operator takes hold of the rear ends of the nut carrying levers 55 and 95 presses them together in opposition to their spring, thereby releasing the nut from the feed screw, which permits the slide to be pulled rearward to its starting point.

During this first described cycle of operations one side of the buttonhole is finished, let us say, for example, the right side. This is because the workholder is vibrated from the line of the buttonhole to the right therefrom and back and forth between these positions. To finish the left side of the buttonhole one shifts the position of the base 12 upon the subbase 10. To enable this to be done the base has two laterally extended slots 60 through it; and studs 61 fixed to the sub 100 base projecting up through these slots. In the base likewise is a slot 62, and through this slot passes an eccentric 63 that is pivoted to the subbase, and has an operating lever 64 on its upper end. By turning this 105 lever the eccentric will move the base upon the subbase to right or left a distance of approximately $\frac{1}{8}$ inch, and this sets the mechanism in readiness for forming the other side of the buttonhole. This eccentric 110 base shifting mechanism is also useful in that it provides means for finishing the ends of the buttonhole. When the end of the buttonhole is reached the operator may, when the needle goes up from the outer edge 115 of one row of stitches, shift the base, which will result in the descent of the needle at a point in line with the outer edge of the other row of stitches,—that is to say, the stitch made will be twice as long as the ordinary 120 125 130

stitches. In making these long finishing stitches it is desirable that the slide have no endwise feed movement. Therefore, in order to hold the half nuts out of engagement 5 with the feed screw so that the workman may have both hands free the loop 70 is provided. This embraces both levers, but when near their pivots, it does not interfere with their movement such as will carry them into 10 engagement with the feed screw. But by sliding said loop forward toward the ends of the levers when they are open, and it will hold them open, that is, will prevent the two half nuts from engaging the feed screw.

15 Having described my invention, I claim:
 1. In a buttonhole attachment for sewing machines, the combination of a base, a guided slide mounted thereon and movable forward and backward, and having a down- 20 turned front end, a feed screw located below and mounted upon the base and passing forward through a hole in the downturned front end of the slide, a pinion fixed to said feed screw, and means carried by the slide 25 for disengaging said feed screw, and a rotating element lying above and mounted upon a vertical axis upon said base, and comprising as a lower member a disk in which are slots to receive the teeth of said 30 pinion, a cam having an uneven number of cam projections, and a ratchet disk having double that number of upwardly projecting pins, a vibrating workholder pivoted on a vertical axis to said slide and having 35 along its sides downturned edges adapted to be engaged by said cam projections, a standard fixed to said base, a bell crank lever pivoted thereto having a horizontal arm adapted to engage the reciprocating 40 needle bar of the sewing machine and having also a downturned arm and a spring pawl carried by said downturned arm to engage the pins on said ratchet disk.

2. In a buttonhole attachment for a sewing machine, the combination of a subbase 45 adapted to be attached to the sewing machine, a base mounted and movable laterally thereon, means to effect and prevent such lateral movement, a slide movably mounted 50 upon said base and movable forward and backward thereon, a vibrating workholder pivoted to said slide on a vertical axis, a feed screw mounted on the base for operating said slide, a rotatable element mounted 55 on a vertical axis upon the base and includ- 60 ing a ratchet by which it is turned, a cam which engages the vibrating workholder to vibrate it back and forth, and a gear, an intermeshing gear fixed to the feed screw, a standard fixed to the base, a lever pivoted to said standard and carrying a pawl for engaging said ratchet, said lever being

adapted to be engaged and operated by the reciprocating needle bar of the sewing machine.

3. In a buttonhole attachment for a sewing machine, the combination of a base, a slide mounted thereon and movable forward and backward and having a downturned front end, a feed screw located below and mounted upon the base and passing forward through a hole in the downturned front end of the slide, a pair of levers mounted on the downturned part of said slide and each carrying a half nut adapted to engage said feed 70 screw or to be disengaged therefrom as required, means for holding said half nuts disengaged from said feed screw, a vibrating workholder pivoted on a vertical axis on said slide and extending rearward therefrom,—said workholder having downturned flanges along its sides, a rotating element mounted on a vertical axis upon said base and comprising a ratchet by which it may be turned, a gear for turning the feed screw, 80 and a cam having an uneven number of cam projections adapted to engage the downturned flanges of said vibrating workholder, a gear fixed to said feed screw and in mesh with the gear which is a part of said rotating element, a standard fixed to said base, a lever mounted thereon and adapted to be engaged and operated by the reciprocating needle bar of the sewing machine, and a pawl carried by said lever for actuating 90 said ratchet.

4. In a buttonhole attachment for sewing machines, the combination of a base, a slide mounted thereon and movable forward and backward, a screw mounted upon the base, means carried by the slide for engaging and disengaging said screw, a vibrating workholder pivoted on a vertical axis on said slide adjacent the front end thereof and extending rearward therefrom, said workholder having downturned flanges along its sides, a rotating element mounted on a vertical axis upon said base and comprising a ratchet by which it may be turned, a gear for turning the feed screw, and a cam lying between said downturned flanges and having an uneven number of cam projections adapted to engage said downturned flanges of the vibrating workholder, a gear fixed to said feed screw in mesh with the gear which is a part of said rotating element, a standard fixed to said base, a lever mounted on said standard and adapted to be engaged and operated by the reciprocating needle bar of a sewing machine, and a pawl carried by said lever for actuating said ratchet.

In testimony whereof, I hereunto affix my signature.

FREDERICK D. SWEET.
